CLAIM

The ornamental design for a voice recording/reproducing device, as shown and described.

DESCRIPTION

FIG. 1 is a front, top and right side perspective view of a voice recording/reproducing device showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken line depiction of portions of the voice recording/reproducing device is for the purpose of illustrating unclaimed portions of the design and forms no part thereof.
